(57) **CLAIM**

The ornamental design for a motorcycle driver footboard, as shown and described.

DESCRIPTION

FIG. 1 is a perspective view of a motorcycle driver footboard.

FIG. 2 is a top plan view of the motorcycle driver footboard. FIG. 3 is a bottom plan view of the motorcycle driver footboard.

FIG. 4 is a right side elevational view of the motorcycle driver footboard.

FIG. 5 is a left side elevational view of the motorcycle driver footboard.

FIG. 6 is a front elevational view of the motorcycle driver footboard; and,

FIG. 7 is a rear elevational view of the motorcycle driver footboard.

Parts shown in broken lines in the figures are shown for illustrative purposes only and form no part of the claimed design.
